UNITED STATES PATENT OFFICE.

• PETER FRIIS AND HENRY A. WAHLEN, OF RACINE, WISCONSIN, ASSIGNEES TO THE BEARDSLEY & PIPER COMPANY, OF CHICAGO, ILLINOIS, A CORPORATION OF ILLINOIS.

MOLDING MACHINE.

Application filed December 7, 1921. Serial No. 520,498.

To all whom it may concern:

Be it known that we, PETER FRIIS and HENRY A. WAHLEN, both citizens of the United States, and residents of Racine, in the county of Racine and State of Wisconsin, have invented certain new and useful Improvements in Molding Machines, of which the following is a full, clear, and exact description.

10 The invention relates to molding machines. In using machines of the type exemplified in the patents to Beardsley and Piper No. 1,309,833 and No. 1,335,642 for making some moulds, it has been found advantageous to dispense with all of the inclined chutes for feeding sand to the projector, particularly where it is desired to feed sand in great volume to the projector, for example, in making moulds for piano-
20 plates. One object of the invention is to provide an improved machine to meet this condition. Another object of the invention is to combine with a riddle, a feed-belt which is adapted to quickly remove the riddled sand from the riddle. Another object is to provide a molding machine of the aforesaid type of improved construction.

25 The invention consists in the several novel features hereinafter set forth and more particularly defined by claims at the conclusion hereof.

In the drawings: Fig. 1 is a side elevation of a machine embodying the invention. Fig. 2 is a plan. Fig. 3 is a vertical longitudinal section of the sand feeding apparatus. Fig. 35 4 is a section taken on line 4—4 of Fig. 3. Fig. 5 is a section taken on line 5—5 of Fig. 3. Fig. 6 is a longitudinal section through the projector. Fig. 7 is a transverse section 40 through the projector.

The invention is exemplified in a structure comprising a mast or vertical support 10 on the upper end of which is journalled for horizontal rotation a socket 13, to which a horizontal tubular jib 12 is secured. An arm 14 is suitably pivoted to the distal end of the jib so as to swing laterally relatively thereto, and a sand projector comprising a casing or stator 15 and a rotor 16 provided 45 with a shear and projector-blade 17 which may be of the construction set forth in the aforesaid Patent No. 1,309,833. The rotor 16 is fixed to a shaft 18 which extends longitudinally through the arm 14 and is driven

by an electric motor 19 disposed adjacent 55 the inner end of said arm.

Mechanism for feeding sand to the projector in regular and desired volume comprises an endless belt 20 carried by rollers 21 and 22 which are journalled in a framework which is rigidly secured to turn horizontally with the jib 12. Said framework comprises standards 23 and brackets 24 in which roller 21 is journalled, and supporting members 25 provided with brackets 26 in 60 which the roller 22 is journalled. The parts of this framework are rigidly secured together to support the rollers so they will swing laterally with the jib 12. A roller 22' is provided to support the medial portion of 65 the belt 20 and is supported by a member 22^a fixed to the framework 23, 25. A chute 27 is fixedly secured to the upper ends of members 23 and 25, so that it will also move with the jib 12 and belt 20. A stationary 70 chute 28 is adapted to deliver sand into that end of the chute 27 which is disposed adjacent the pivoted end of the jib 12. A riddle, slightly inclined downwardly towards the discharge end of the belt 20, comprises a 75 sifting element 29 and a frame 30. One end of the riddle is supported by arms 31 which are pivoted at 32 in bearings 33 which are fixed to the elongated chute 27. The other end of the riddle is reciprocably guided 80 between rollers 34 which are mounted in the chute and on the sides thereof. Chute 27 is elongated to extend longitudinally over the feed belt 20 so that any material which will become sufficiently disintegrated to pass 85 through the screen will fall onto the belt 20. The lower portion of chute 27 is provided with a tapered portion 27^a so that a riddle considerably wider than the belt may be 90 used and so that the riddle will be of sufficient capacity to supply a large volume of screened sand to the projector. Arms 31^a are rigid with arms 31 and mechanism is provided for operating said arms to vibrate 95 the riddle longitudinally in the chute 27. 100

This mechanism comprises an electric motor 34 mounted on a bracket 35 which is fixed to socket 13 and is horizontally rotatable with the jib and other parts carried thereby: a shaft 36 driven by said motor and provided with a worm-gear 37 in a gear-casing 38 which meshes with a gear 39 also enclosed in said case; a sprocket-wheel 40

secured to be driven by the shaft 41 of gear 39; a sprocket-chain 42 driven by said sprocket wheel; a sprocket wheel 43 driven by said chain and fixed to the shaft 44 of 5 the roller 21; cranks 45 on shaft 44 and pitmen 46 connected to said cranks and to arms 31^a. The motor 34 and reducing gear and chain drive 40, 42, 43 also serve to drive the sand-feeding belt 20. The sand fed to 10 the riddle frequently contains scrap castings and these, as well as the lumps of sand which are not disintegrated, are discharged from the end of the sieve 29 into a cross-duct 48 with an inclined bottom 49 which 15 discharges the material at one side of the belt 20 and into a chute 50 which is secured to the framework 23, 25 on the jib. A box 51 secured to the jib 12 receives the material from the chute 50. The structure thus far 20 described exemplifies mechanism for feeding sand which is mounted to rotate horizontally with a jib and comprises an endless belt and a riddle above the belt for delivering sand in great volumes onto the belt.

25 The discharge end of belt 20 and roller 22 are disposed so the riddled sand from said belt will be discharged into a hopper 54 which is mounted on arm 14 and movable therewith, being secured thereto by supports 30 55 and 56. The bottom of chute 54 is open so the sand will fall upon an endless belt 57 which passes around rollers 58 and 59, both of which are suitably supported on, and to swing horizontally with, the arm 14. Chute 35 54 and the roller 58, which is disposed adjacent the receiving end of the belt 57, are disposed above and near the axis of the pivot 14^a around which the arm 14 swings relatively to the jib 12, so that the hopper 54 40 and belt 57 will receive sand from the belt 20 in all of the angular positions of the arm and the jib. The discharge end of belt 57 delivers the sand into the projector, as exemplified in our said Patent No. 1,335,642.

45 Belt 57 is driven to continuously feed sand to the projector by mechanism comprising a bevelled gear 60 on the shaft 18 between the motor 19 and the rotor 16, a bevelled gear 61 meshing with gear 60, an idler 62 which 50 meshes with a gear 63 rigid with gear 61 and with a gear 64 fixed to the shaft of roller 58. This mechanism is suitably mounted on a case 65 which forms a part of the arm 14 and is secured to the case of the 55 motor 19. This construction exemplifies an arm, on the distal end of which the projector is secured, and a belt for feeding sand to the projector from a belt which is movable relatively to the arm and with a pivoted jib.

60 In operation, the sand is delivered through chute 28 onto the receiving end of the riddle in chute 27. The latter is vibrated by the mechanism driven from motor 34, so that the sand will be sifted thereby and fall 65 through the chute and onto the belt 20. The

deposit of the sand from the riddle will be gradual as it becomes disintegrated in passing over the riddle. Any lumps or scrap with the sand will be discharged from the outer end of the riddle into the duct 48 so 70 that they will not be delivered to the projector. The sand deposited on the belt 20 will be discharged at roller 22 into the hopper 54 which will guide it onto the receiving end of the belt 57 which will convey 75 the sand to the projector. The latter, being operated at high speed from the motor 19, will forcibly project wads of sand sheared from the stream discharged from belt 57 into a flask beneath the projector, 80 as well understood in the art. The pivotal movement of the jib 12 and arm 14 and the relative movement between them permit the projector to be moved over and project sand into all portions of a flask, to properly form 85 and pack a mould.

The receiving end of chute 27 and the riddle therein are disposed over the axis of the pivot between the jib 12 and support 10, so that they will receive sand from the stationary hopper 28 in all positions of the 90 jib 12.

The invention exemplifies a molding machine in which the sand projector is supplied with sand by mechanism comprising a plurality of sand-feeding belts which are mounted to move with relatively movable supporting members, one belt being adapted to deliver sand to the other belt. The invention also exemplifies a molding machine 95 in which a riddle is adapted to deposit the sifted sand onto a belt and which operates in an elongated chute which is movable horizontally with the belt so that it is necessary to vibrate the chute. 100

The invention is not to be understood as restricted to the details set forth, since these may be modified within the scope of the appended claims, without departing from the spirit and scope of the invention. 105

Having thus described the invention, what I claim as new and desire to secure by Letters Patent, is:

1. In a molding machine, the combination of a plurality of horizontally swinging members, one of which is pivoted to the other, a sand-projector on one of said members, a plurality of sand feeding belts mounted to move with said members respectively, one of which is mounted to deliver sand to the projector, mechanism for driving said belts, and mechanism for operating said projector. 115

2. In a molding machine, the combination of a plurality of horizontally swinging members, one of which is pivoted to the other, a sand projector on one of said members, a plurality of sand feeding belts mounted to move with said members respectively, one of which belts is mounted to 120

125

deliver sand to the other, the latter being mounted to deliver sand to the projector, and mechanism for driving said belts.

3. In a molding machine, the combination of a plurality of horizontally swinging members, one of which is pivoted to the other, a sand projector on one of said members, a plurality of sand feeding belts, mounted to move with said members respectively, one of which belts is mounted to deliver sand to the other in all angular positions, the latter being mounted to deliver sand to the projector, mechanism for driving said belts, and mechanism for operating said projector.

4. In a molding machine, the combination of a plurality of relatively movable supporting members, a sand projector mounted on one of the members, a plurality of sand feeding belts mounted on the members respectively, a riddle over one of said belts, mechanism for operating the riddle, mechanism for driving the belts, and mechanism for operating the projector.

5. In a molding machine, the combination of a plurality of horizontally swinging supporting members, a sand projector mounted on one of the members, a plurality of sand feeding belts mounted on the members respectively, a riddle over one of said belts, mechanism for operating the riddle, mechanism for driving the belts, and mechanism for operating the projector.

6. In a molding machine, the combination of a plurality of horizontally swinging supporting members, a sand projector mounted on the end of one of the members, a plurality of sand feeding belts mounted on the members respectively, a vibratory riddle over one of said belts, mechanism for operating the riddle, mechanism for driving the belts, and mechanism for operating the projector.

7. In a molding machine, the combination of a vertical support, a horizontally swinging arm pivoted thereto, a second horizontally swinging arm pivoted to the first arm, a sand-projector, means for operating the projector carried by the second arm, two sand conveyor belts, one carried by each arm, that on the first arm delivering sand to the second belt in all angular positions of the two arms to each other, the second conveyor belt delivering sand to the projector, and mechanism for driving said belts.

8. In a molding machine, the combination of a vertical support, a horizontally swinging arm pivoted thereto, a second horizontally swinging arm pivoted to the first arm, a sand-projector, means for operating the projector carried by the second arm, two sand conveyor belts, one carried by each arm, that on the first arm delivering sand to the second belt, in all angular positions of

the two arms to each other, the second conveyor belt delivering sand to the projector, mechanism for driving said belts, a vibratory riddle mounted on one of said arms and over one of the belts, and mechanism for operating the riddle.

9. In a molding machine, the combination of a sand projector, supporting means for the projector comprising a movable member, means to feed sand to the projector comprising a belt mounted to move with said member, a riddle also mounted on said member and adapted to discharge sand to the belt, mechanism for operating the riddle, and mechanism for driving the belt.

10. In a molding machine, the combination of a sand projector, supporting means for the projector comprising a pivoted member, means to feed sand to the projector comprising a belt mounted to swing with said member, a riddle also mounted on and to move with said member and adapted to discharge sand onto said belt, and mechanism for operating the riddle and for driving the belt.

11. In a molding machine, the combination of a sand projector, supporting means for the projector comprising a movable member, means to feed sand to the projector comprising a belt mounted to move with said member, a riddle also mounted on said member, mechanism for conjointly operating the riddle and driving the belt.

12. In a molding machine, the combination of a horizontally movable member, a movably supported sand projector, means to feed sand to the projector comprising a chute fixedly mounted on said member, a vibratory riddle in said chute, mechanism for operating said riddle, and mechanism for operating the projector.

13. In a molding machine, the combination of a horizontally movable member, a movably supported sand projector, means to feed sand to the projector comprising a chute fixedly mounted on said member, a vibratory riddle in said chute, said chute and riddle being wider than said belt, mechanism for operating said riddle, and mechanism for operating the projector.

14. In a molding machine, the combination of a horizontally movable member, a movably supported sand projector, means to feed sand to the projector comprising a chute fixedly mounted on said member, a vibratory riddle in said chute, said chute and riddle being wider than said belt, the chute having a constricted lower portion to guide the sand to the belt, mechanism for operating said riddle, and mechanism for operating the projector.

15. In a molding machine, the combination of a horizontally movable member, a movably supported sand projector, means to feed sand to the projector comprising a chute fixedly mounted on said member, a vibratory

- 1 riddle in said chute, means to conduct the material retained by the riddle to one side of the belt, mechanism for operating said riddle, and mechanism for operating the projector. 5
16. In a molding machine, the combination of a horizontally swinging member, a movably supported sand projector, means to feed sand to the projector comprising a belt 10 movable with said member, a chute fixedly mounted on said member, a vibratory riddle in said chute adapted to deposit sand on the belt, mechanism for operating said riddle and said belt, and mechanism for operating 15 the projector.
17. In a molding machine, the combination of a plurality of horizontally swinging members, a sand projector on one of said members, means to feed sand to the projector comprising a belt movable with one of said members, a chute fixedly mounted on said latter member, a vibratory riddle in said chute and adapted to deposit sand on the belt, mechanism for operating said riddle 20 and said belt, and mechanism for operating the projector.
18. In a molding machine, the combination of a vertical support, a horizontally swinging arm pivoted thereto, a second horizontally swinging arm pivoted to the first arm, 25 a sand projector on said second arm, means for operating the projector carried by the second arm, two sand conveyor belts, one carried by each arm, that on the first arm delivering sand to the second belt in all angular positions of the two arms to each other, the second conveyor belt delivering to the sand projector, and separate mechanisms for driving said belts. 30
19. In a molding machine, the combination of a vertical support, a horizontally swinging arm pivoted thereto, a second horizontally swinging arm pivoted to the first arm, 35 a sand projector on said second arm, means for operating the projector carried by the second arm, two sand conveyor belts, one carried by each arm, that on the first arm delivering sand to the second belt in all angular positions of the two arms to each other, the second conveyor belt delivering to the sand projector, mechanism for driving said belts, a vibratory riddle mounted on one of said arms and over one of the belts, and mechanism for conjointly operating the riddle and driving one of the belts. 40
